(57) **CLAIM**

The ornamental design for the link bridge, as shown and described.

DESCRIPTION

FIG. 1 is a perspective view of the link bridge embodying my new design and shown attached to inner plates of a chain.

FIG. 2 is a side view of the link bridge shown in FIG. 1.

FIG. 3 is a top view of the link bridge shown in FIG. 1.

FIG. 4 is an end view of the link bridge shown in FIG. 1.

FIG. 5 is a bottom view of the link bridge shown in FIG. 1.

FIG. 6 is a perspective view of an alternative embodiment of the link bridge shown in FIG. 1.

FIG. 7 is a side view of the link bridge shown in FIG. 6.

FIG. 8 is a top view of the link bridge shown in FIG. 6.

FIG. 9 is an end view of the link bridge shown in FIG. 6; and,

FIG. 10 is a bottom view of the link bridge shown in FIG. 6.

In the drawings, the broken line showing of inner plates of a chain depicts environmental subject matter and forms no part of the claim.

1 Claim, 4 Drawing Sheets
